(57) **CLAIM**

The ornamental design for a flexible electronic tablet, as shown and described.

DESCRIPTION

FIG. 1 is a front perspective view of a flexible electronic tablet showing the new design in a flat position.

FIG. 2 is a rear perspective view thereof.

FIG. 3 is a front elevation view thereof.

FIG. 4 is a rear elevation view thereof.

FIG. 5 is a left side view thereof.

FIG. 6 is a right side view thereof.

FIG. 7 is a top view thereof.

FIG. 8 is a bottom view thereof.

FIG. 9 is a front perspective view of the flexible electronic tablet of FIG. 1 shown in a flexed position.

FIG. 10 is a front elevation view thereof.

FIG. 11 is a rear elevation view thereof.

FIG. 12 is a left side view thereof.

FIG. 13 is a right side view thereof.

FIG. 14 is a top view thereof.

FIG. 15 is a bottom view thereof.

FIG. 16 is a front perspective view of the flexible electronic table of FIG. 1 shown in a second flexed position; and,

FIG. 17 is a bottom view thereof.
